PAGE 2

FIG. 3.

Fig. 5.

Fig. 6.

FIG. 1 is a front perspective view of a book truck showing my new design;

FIG. 2 is an end perspective view of the same book truck;

FIG. 3 is a top plan view of the truck of FIGS. 2 and 3;

FIG. 4 is a front perspective view of a modified form of a book truck showing my new design as used in a 5-shelf arrangement;

FIG. 5 is a perspective view of the arrangement of FIG. 4 showing the rear and side thereof;

FIG. 6 is a top plan view of the arrangement of FIG. 4;

FIG. 7 is a front perspective view of another modified form of a book truck showing my new design as used in a 3-shelf arrangement;

FIG. 8 is a perspective view of the arrangement of FIG. 7 showing the rear and side thereof; and

FIG. 9 is a top plan view of the arrangement of FIG. 7.

The rear not shown of the arrangement of FIGS. 1 through 3 is identical in appearance to the front shown in FIG. 1.

The side not shown for the arrangement of FIGS. 4 through 6 is identical in appearance to the side shown in FIG. 4.

The side not shown for the arrangement of FIGS. 7 through 9 is identical in appearance to the side shown in FIG. 7.

This application is a continuation of my co-pending applications Serial Nos. D. 68,263, filed January 11, 1962 and now abandoned; D. 70,691, filed June 26, 1962; D. 70,096, filed May 14, 1962; and D. 70,097, filed May 14, 1962.

I claim:

The ornamental design for a book truck, substantially as shown and described.
